United States Patent Office.

JACOB B. BYERS, OF GENESEO, ILLINOIS.

Letters Patent No. 72,451, dated December 24, 1867.

IMPROVED WASHING-MACHINE.

The Schedule referred to in these Letters Patent and making part of the same.

TO ALL WHOM IT MAY CONCERN:

Be it known that I, J. B. BYERS, of Genesee, in the county of Henry, and State of Illinois, have invented new and useful Improvements in Washing-Machines; and I do hereby declare that the following is a full and exact description thereof, reference being had to the accompanying drawings, making part of this specification, in which—

Figure 1 is the section of the box and the section of both beaters, and

Figure 2 is the top view of the machine without the cover.

The nature of my invention consists in the beaters, so constructed that they throw up and stir the cloth, working it against a curved corrugated front of the wash-box; also, in the shape of the wash-box itself, which shape permits the cloth to be washed with a less quantity of suds than in other machines; also, in providing two openings to catch water from the wringer, and convey it into the wash-box, said openings so arranged that no water or suds can splash out through them, as will be hereinafter fully explained.

To enable others skilled in the art to make and use my invention, I will proceed to describe its construction and operation.

A is a wash-box, provided with slanting bottom, B, and a separate curved and corrugated front partition, C, against which the beaters are working, the slanting bottom permitting the use of but a small quantity of suds at a time. D D are the beaters, shaped like shoes, and consisting of the bottom plate d, side pieces d', and cross-pieces d'', the side pieces being hung on to a rod, E, on which they partially revolve. The movement to the beaters is communicated by the connecting-rods F F, hinged at one end to the bottom plate, d, of the beaters, and hung on to the crank-shaft G, journaled to the box A, and provided with a crank-handle, H, at one end, and a fly-wheel at the other. There is a trough, K, to the outside of which a wringer may be attached. Said trough has bottom made of perforated metal, to prevent the water from splashing out of the box when the machine is in operation. Trough L is to catch water on the outside of the wringer, and convey it into the space M of the box, between the front side of the same and the corrugated surface C. There is an opening, m, at the bottom of the surface C, to communicate with the space M, and a faucet, N, to discharge the suds from the box.

The operation of the machine consists in that the box is filled with suds, and the cloth is put in the space between the beaters and the corrugated surface C, and as the machine works, the beaters throw up the cloth and work it against the surface C, which surface, and the bottom plate and cross-pieces of the beaters, wash it thoroughly.

What I claim as my invention, and desire to secure by Letters Patent, is—

A washing-machine, having the stationary inclined corrugated board C and the swinging beaters D, suspended and pivoted within the box A with the inclined bottom B, all arranged as shown and described.
